PHOTOGRAPHIC DEVELOPING
APPARATUS

Benjamin James Hall, Westminster, England

Application June 1, 1933, Serial No. 673,897
In Great Britain June 17, 1932

5 Claims. (Cl. 95—94)

This invention relates to photographic apparatus in which the development of photographic prints is carried out by exposure to a gaseous vapour or gas impregnated atmosphere, the prints being exposed to the action of the vapour by carrying them between or upon fabric bands, fabric covered drums or other suitable surfaces and whereas it has been the custom to accelerate the formation of gaseous vapours by applying heat to the volatile liquid or liquids and further to free the photographic prints from clinging vapours by allowing them to fall into an airing chamber from which the vapours are extracted by ventilation, I have discovered that the acceleration of volatilization can be more efficiently performed by introducing the volatile liquid or liquids into the chamber at a normal temperature and by heating the surfaces where development is to take place, in particular maintaining such surfaces as it is desirable to keep free from the moisture of condensation, at a higher temperature than any other part of the apparatus. By so doing the prints pass through the apparatus in a comparatively dry condition and there is no disturbance caused by the condensation of moisture upon the parts of the machine with which the prints come in contact.

By this means the quality of the product is improved, considerable saving in the use of volatile liquid is effected and the discharge of fumes diminished.

To free the prints from clinging vapours, I provide a purifying chamber into which the prints pass between a heated surface and an absorbent surface. These surfaces may be in direct contact or separated slightly one from the other—they may be stationary or one or both may have motion imparted to them.

In cases where it is not convenient to use a ventilating pipe, exhaust fan or any like means of discharging fumes from the apparatus, I provide a water tank, tanks, spray or sprays or other means of condensation within the outer casing which encloses the apparatus.

45 The invention is illustrated on the accompanying drawing, in which

Fig. 1 is a sectional diagrammatic view of one form of my invention;

50 Fig. 2 is a sectional diagrammatic view of an alternative form of the invention disclosed by Fig. 1;

Fig. 3 is a sectional diagrammatic view of a modification of my invention;

55 Fig. 4 is a sectional diagrammatic view of an

alternative form of the heating means used in Fig. 3;

Fig. 5 is a sectional diagrammatic view of a further modification of the invention;

Fig. 6 is a sectional diagrammatic view of a purifying chamber used with my invention; and

Fig. 7 is a sectional diagrammatic view of a modification of the purifying chamber of Fig. 6.

In the apparatus shown by Fig. 1 I employ two fabric bands in contact A, A¹, suitably mounted in the chamber B. The contiguous surfaces of the bands are supported by solid or perforated plates D, D¹, the surfaces of which plates, curved or flat as required, are kept at the desired temperature by the heating elements E, E¹, by hot water circulation or other convenient method. The volatile liquid may be applied to one or both bands, in any position and by any means in which it can be most conveniently absorbed, and preferably by a pipe or pipes F, F¹, running the full width of the band.

The print enters the apparatus through the slit b¹ and is discharged through the slit b² provided in the chamber B for the purpose.

At Fig. 2 I have shown diagrammatically an apparatus in which I employ a single fabric band A in contact with a solid or perforated metal plate D, the surface of which plate, curved or flat as required, is kept at the desired temperature by the heating elements E, or by hot water circulation or other convenient heating method. A supplementary plate D¹ and heaters E¹ may be introduced above the band A if desired.

The print enters the apparatus at b¹ and is discharged at b².

In the apparatus shown diagrammatically at Fig. 3 I employ a non-absorbent band A in contact with a curved or flat perforated plate or grid D forming one side of a chamber H in which the volatile liquid enters and is vaporized by heater h¹. The underside surface of the plate D is heated by the heating elements E, suitably positioned to obtain the requisite degree of temperature. Or the perforated surface or grid D may be heated by hot water circulation as shown diagrammatically at Fig. 4. The print enters the apparatus at b¹ and is discharged at b².

At Fig. 5 I have shown a form of apparatus in which I employ a fabric covered drum J revolving in contact with a solid or perforated curved metal plate D, the surface of which plate is kept at the desired temperature by heaters E, by hot water circulation or other convenient means.

The liquid to be volatilized is conveyed to the

fabric in any convenient way, by preference through the hollow spindle j^1 of the drum J.

The mouth of the casing B in which the drum revolves is closed at K with the exception of two full width slots k^1 , k^2 , for feeding and discharge, arranged at any desired distance from each other. The upper horizontal wall of the slot k^1 is perforated at k^3 to allow the escape of vapours to the outer casing B, and both walls of the slots k^1 , k^2 are heated by the heating elements e^1 to prevent condensation.

To free the prints issuing from the developing apparatus from clinging vapours I may provide a purifying chamber, such purifying chamber, which is intended for use in connection with any of the foregoing developing apparatus, being placed at the slot through which the print issues from the developing apparatus.

The purifying chamber, illustrated diagrammatically at Fig. 6 comprises a casing B in which an absorbent endless band A, moving round rollers a^a , is arranged, a water tank L or air cooled chamber being provided in the base of the casing B. The upper wall of the slot through which the print travels on issuing from the developing apparatus is formed by the plate N, such plate N being warmed by the heaters E, or by hot water circulation or by any other suitable method. Or instead of employing the plate N in conjunction with the moving band A, I may employ two travelling bands, the upper one of which is heated and the lower cooled, or vice versa.

At Fig. 7 I have shown a further modification of the purifying chamber. In this case instead of a moving absorbent band I may provide a fixed absorbent surface P, between which surface and the warmed plate N the print is caused to travel.

What I claim as my invention and desire to secure by Letters Patent is:—

1. An apparatus for the development of light sensitive sheet material comprising a casing having end, side, bottom and top walls, an entrance slot for sensitized sheet material in one side wall, an exit slot in the opposite wall and aligned with said first slot, spaced and parallel plates within said casing and defining a narrow passage therein between said slots, separate heating means for each plate and adjacent thereto, an endless and absorbent conveyor in the upper portion of said casing and extending around the upper plate, a second endless absorbent conveyor in the lower portion of said casing and extending around the lower plate and so arranged as to contact with said first conveyor between said plates, separate means for introducing a volatile developing liquid to each of said conveyors, and said heating means being adapted to heat said plates and

also to accelerate the volatilization of said liquid.

2. An apparatus for the development of light sensitive sheet material, comprising a casing having end, side, bottom, and top walls, an entrance slot for said sheet material in one side wall, an exit slot in the opposite side wall and aligned with said first slot, spaced and parallel plates within said casing and defining a narrow passage therein between said slots, endless and absorbent conveying means within said casing for conveying said material through said casing between said plates, means for introducing a volatile developing liquid to said conveying means, separate means for heating each of said plates and adjacent thereto, said last named means also serving to aid in the volatilization of said liquid.

3. An apparatus for the development of light sensitive sheet material, comprising a casing, entrance and exit slots in said casing, a narrow passage having top and bottom walls connecting said slots, endless and absorbent conveying means within said casing for conveying said sheet material through said passage, separate means for heating both the top and the bottom walls of said passage throughout their length, means for introducing a volatile developing liquid to said conveying means, and said heating means also serving to accelerate the volatilization of said liquid.

4. An apparatus for the development of light sensitive sheet material, comprising a casing having side, end, bottom, and top walls, an entrance slot for sensitized sheet material in one side wall, an exit slot in the opposite side wall and aligned with said first slot, spaced and parallel plates within said casing and defining a narrow passage therein between said slots, separate means for heating each plate throughout its length, an endless and absorbent conveyor in the upper portion of said casing and extending around the upper plate, means for introducing a volatile developing liquid to said conveyor, and said heating means also serving to accelerate the volatilization of said liquid.

5. An apparatus for the development of light sensitive sheet material, comprising a casing having side, end, bottom, and top walls, spaced entrance and exit slots in one of said side walls, narrow passages extending inwardly of said casing from said slots and terminating on opposite sides of a cylindrical chamber, an absorbent conveying cylinder rotatably mounted in said chamber, means for introducing a volatile developing liquid to said cylinder, and separate means for heating the top, and bottom walls of said passages throughout their length and means for heating the defining wall of said chamber.

BENJAMIN JAMES HALL.
